UNITED STATES PATENT OFFICE

IRVEN H. WILSEY, OF CHICAGO, ILLINOIS

AIR CLEANER

Application filed October 3, 1924. Serial No. 741,516.

This invention relates to improvements in air cleaners, and more specifically cleaners adapted to supply clean, pure air to carburetors on internal combustion engines.

5 An important object of the invention is to provide a simple and inexpensive air cleaner of novel construction which is highly efficient over a wide range of air supply.

Another object is to provide a new and 10 improved air cleaner which is adapted to utilize the air flow from the radiator fan of an automobile, and which is so constructed that no material loss of power results from the actual cleaning.

15 A further object of my invention resides in the provision of an air cleaner having novel means for effecting a ready removal of the foreign particles separated and collected from the flowing air.

20 Still another object is to provide an air cleaner for carburetors which can be built in or combined with some standard automobile part, such as the signal horn, to obtain a single unitary device for performing a plurality of functions.

25 A further object resides in the provision of a method for supplying clean air to a carburetor, which method comprises inducing a flow of air through a conical or tapering tube into a separating chamber, and deflecting a portion of said air into a passage leading to the carburetor but permitting the remaining portion of air to continue on substantially in its original direction, the ratio of 30 said two portions being such that the gain in static pressure due to the sudden change in direction of the deflected stream is greater than the loss in static pressure occasioned by the onward flow of the small stream.

40 Other objects and advantages will become apparent as the description proceeds.

In the accompanying drawings, Figure 1 is a fragmentary view of an internal combustion engine on which a device embodying the features of my invention has been mounted.

45 Fig. 2 is a longitudinal section of the air cleaner.

Fig. 3 is a section taken along line 3—3 of Fig. 2.

50 While my invention is susceptible of vari-

ous modifications and alternative constructions, I have shown in the drawings and will herein describe in detail the preferred embodiment, but it is to be understood that I do not thereby intend to limit the invention to the specific form disclosed, but aim in the appended claims to cover all forms falling within the spirit and scope of the invention.

55 Referring to the drawings, 10 represents the carburetor, 11 the intake manifold of an internal combustion engine, 12 the radiator fan at the front of the engine, and 13 the air cleaner in its exemplary embodiment. The engine with its standard equipment is shown diagrammatically and only with such 60 details as are necessary to illustrate the invention.

65 The air cleaner 13 comprises an elongated casing in the form of a conical or tapering tube 14, the large end of which opens next to and just back of the fan 12 and the small end of which extends into the front end of a closed casing 15 defining a suitable dust or separating chamber. A suitable pipe 16 70 opening into the side of the casing 15, connects the latter with the carburetor 10.

75 Fitting closely within the rear end of the casing 15 is a closure comprising a plate 17 of any suitable form or shape. A plurality of fins or vanes 18 mounted on the plate 17 80 and extending across the inner end of the tube 14 serve with the closure to deflect and whirl the incoming air about in the casing 15, and to define relatively dead air pockets for 85 separating and collecting the foreign particles entrained in the air. These fins can be of any desired form and arranged in any suitable way, but preferably they consist of a set of parallel plates spaced equidistantly and extending transversely of the pipe connection 16.

90 Means is provided for continuously permitting the efficient removal of the waste particles collected from the air. To this end, the plate 17 is provided with a plurality of 95 equally spaced peripheral projections 19 which fit snugly against the inner surface of the casing 15 and serve to provide a plurality of arcuate spaces or ports 20 at and about the inner periphery of the casing.

In the present instance, the air cleaner is constructed to form part of a standard signal device for automobiles, the tube 14 serving as the air inlet for the cleaner, and also constituting the horn of the signal device. The signal device comprises a motor 21, the casing of which extends into the rear end of the casing 15, and which is closed at its inner end by a vibrating diaphragm 22. The plate 17 herein shown is secured by screws 23 to a flange 24 on the motor casing, and is annular in form to leave the central portion of the diaphragm 22 exposed.

In operation, a flow of air through the tube 14 is induced by the revolving fan 12 and the suction in the carburetor 10. As the air passes in through the tube 14 its velocity is increased at a corresponding loss in static pressure. The air enters the casing 15 at a high velocity, and impinges against the plate 17, fins 18 and diaphragm 22, whereby it is whirled about and deflected into the pipe connection 16. The entrained particles in the air are carried by their inertia into the back of the relatively dead air pockets between the fins 18 and are thereby separated from the deflected air and collected for removal from the casing 15. A portion of the air continues substantially in its original direction through the ports 20 and serves thereby to carry out the foreign particles collected by the fins 18. This action will take place even though the static pressure in the casing 15 is below that of the atmosphere, due primarily to the velocity of the air flowing through the ports 20. The flow of air through the ports 20 has an aspirating effect that causes a slight vacuum or pressure drop in the rear end of the enclosed portion of the casing 15, and thereby facilitates the separation of the foreign particles from the air and their collection for removal from the casing 15. The air flowing around the outside of the casing or chamber 15 also causes an aspiration resulting in a slight vacuum at the rear of the plate 17. Vibration of the diaphragm loosens the particles and aids in removing them.

The sudden change in direction of a major portion of the air converts most of its velocity head to static pressure. This static pressure is considerably more than the loss of static pressure occasioned by the flow of air through the ports 20. In practice, upon increasing the velocity of the incoming air, the static head in the casing 15 can be made to exceed atmospheric pressure thereby resulting in a supercharging effect. Thus the cleaning means serves to clean the incoming air and also tends to create a pressure head to assist the suction in the carburetor 10 in inducing a flow of air through the connection 16. Experiments have shown that a greater suction is required to induce an equivalent flow of air to the carburetor through an open tube than in my device.

It will thus be evident that I have provided a highly efficient air cleaner for supplying pure air to automobile carburetors and other like devices. No movable parts or parts lowering the effectiveness of the carburetor suction are employed in the cleaner. Entrained particles are not whirled along with the air but are immediately separated therefrom and removed from the casing 15. By combining the device with a standard automobile part such as the signal horn, a small unitary device simple, compact and inexpensive for performing a plurality of independent functions is obtained.

I claim as my invention:

1. An air cleaner having, in combination, a casing constituting a dust separating chamber and having an air inlet and an air outlet, and a plurality of spaced dust removing members mounted on one wall of said casing and extending transversely of said air inlet and of said air outlet, said wall serving to deflect the incoming air and said dust removing members serving to provide a plurality of dead air pockets for collecting the matter removed from the air, said wall being formed with a plurality of restricted openings at the closed ends of said pockets for permitting a limited flow of air to scavenge said pockets of foreign matter.

2. An air cleaner having, in combination, a casing constituting a separating chamber and having an outlet, a gradually tapering tube with its small end extending into one end of said casing, means closing the other end of said casing but defining a restricted space to permit the flow of a portion of the air outwardly at the periphery of said casing, and a plurality of vanes mounted on said means in said casing, said vanes extending across the inner end of said tube and substantially at right angles to said outlet.

3. An air cleaner having, in combination, a separating chamber having an air outlet, means for converting the static pressure of air passing therethrough to dynamic pressure and for discharging said air at a high velocity into said chamber, baffle means in said chamber spaced from and extending across the end of said last mentioned means, said baffle means being adapted to deflect the air substantially at right angles into said air outlet, and a plurality of dust separating and collecting vanes on said baffle means, said vanes extending transversely of said first mentioned means and also of said air outlet, said baffle means having openings permitting a restricted flow of air therethrough to carry away foreign matter tending to collect between said vanes.

4. The method of cleaning air, comprising inducing a straight flow of air through a gradually tapering tube, baffling said air after leaving said tube and deflecting a portion of it thereby converting a substantial

part of its velocity head into static head, and permitting another portion of said air to continue on in substantially its original direction to carry out the particles separated from the deflected air, the proportion of the volume of air deflected to that of the air continuing on being such that the loss in static head occasioned by the onward flow of air is substantially less than the gain in static head of the deflected air.

5 5. An air cleaner having, in combination, a casing having an outlet, a gradually tapering tube having its small end projecting into said casing, a plate mounted in said casing opposite said tube, said outlet opening from said casing substantially at right angles to said tube, a plurality of relatively short parallel spaced fins mounted on said plate across the inner end of said tube and at right angles 15 to said outlet, said fins projecting but part way across said outlet, and dust outlet means for permitting a restricted flow of air from between said fins of said casing.

20 6. An air cleaner having, in combination, a casing having an outlet, a gradually tapering tube having its small end extending into one end of said casing, a closure in the other end of said casing, and a plurality of vanes mounted on said closure and extending transversely of said outlet, said closure defining a plurality of openings with the interior of said casing to permit a restricted flow of air about its periphery.

25 7. An air cleaner comprising, in combination, a casing constituting a dust-removing chamber, a discharge passage in said casing, a tapering tube extending into said casing, a plate fitting closely within said casing and defining a plurality of space restricted 30 openings, and a plurality of vanes mounted on said plate and extending across the outlet of said tube.

35 8. An air cleaner comprising, in combination, an air chamber, an intake casing extending into the one end of said chamber, means defining a plurality of relatively dead air pockets at the other end of said chamber to clean and to deflect the air out of said chamber, and a plurality of restricted 40 passages permitting the onward flow of a part of the air in substantially its original direction out of said chamber.

45 In testimony whereof, I have hereunto affixed my signature.

50 IRVEN H. WILSEY.
